UNITED STATES PATENT OFFICE

161,738

PURSE

Ross A. Cowen, New York, N. Y.

Application August 12, 1949, Serial No. 4,444

Term of patent 7 years

(Cl. D87—3)

To all whom it may concern:

Be it known that I, Ross A. Cowen, a citizen of the United States of America, residing at New York, in the county and State of New York, have invented a new, original, and ornamental Design for a Purse, of which the following is a specification, reference being made to the accompanying drawing, forming a part thereof.

Fig. 1 is a front elevational view of a purse, showing my new design;

Fig. 2 is a top plan view thereof with a portion of the handle omitted for convenience of illustration only;

Fig. 3 is a bottom plan view of Fig. 1;

Fig. 4 is an end view of Fig. 1; and

Fig. 5 is an elevational view thereof with the purse in an open position and with a portion of the handle broken away as in Fig. 2 for convenience of illustration.

The back of the purse is the same in appearance as the front.

I claim:

The ornamental design for a purse, substantially as shown and described.

ROSS A. COWEN.
